INVENTOR
John M. Clark
BY
Arthur Phelps Ward
ATTORNEY

UNITED STATES PATENT OFFICE.

JOHN M. CLARK, OF NEW YORK, N. Y.

ANTENNA.

Application filed June 22, 1923. Serial No. 647,057.

The device, the subject of this invention is an antenna, and while it is utilized for the purpose of collecting radio waves and impulses, it is not found necessary to suspend 5 this device at a high elevation.

The principal objects of the invention are to provide a substitute for interior or loop antenna.

A further object of the invention is to 10 provide an antenna having a sufficient normal wave length, without requiring that the antenna itself be of extraordinary length and a still further object of the invention is to provide an antenna that may be used 15 at a point closely approximating, if not actually within the cabinet which contains the amplifying and tuning apparatus and a still further object of the invention is to produce an antenna, exceedingly sensitive to 20 slight waves or impulses.

The means whereby the aforesaid objects are accomplished and the details of construction will be fully set forth as the specification progresses and the accompanying drawing 25 should be referred to for a complete understanding of the specification which follows.

In the drawing:—

Fig. 1, is a side elevation of an antenna 30 of preferred construction.

Figs. 2 to 7 inclusive show modified constructions and means of support.

Fig. 2, is a fractional view in side elevation of a device utilizing a spiral wire.

Fig. 3, a similar view of a device employing 35 a plurality of rods or tubes.

Fig. 4, a similar view of a device showing a modified means of support.

Fig. 5, is a fractured side elevation of a 40 tube having a still further modified supporting means.

Fig. 6, is a sectional view on the line 6—6 in Fig. 5, viewed in the direction of the arrows.

Fig. 7, is a sectional view on the line 7—7 in Fig. 4, the view being taken in the direction of the arrows.

Fig. 8, shows a means of utilizing a series 50 of the devices shown in any of the foregoing views, and

Fig. 9, shows the arrangement of a plurality of devices in the formation of a loop.

Figs. 8 and 9 are in diagram, only.

Fig. 10, is a fractional side elevation of a still further modified construction, and 55

Fig. 11, a sectional view thereof.

Similar reference numerals indicate like parts in all the figures where they appear.

In constructing an antenna, which is to serve as a substitute for the usual suspended 60 wire and one of less area or length than the suspended wire, it is necessary to accomplish desirable results that the substitute be supersensitive and the device which I am about to describe has, under test, demonstrated its 65 possibilities.

My device consists of a glass tube of desirable length; the length which I have found quite satisfactory is about three feet. The tube 10 in Fig. 1, is the tube to which I 70 refer.

Within the tube 10, I place a second tube 11, which may be of copper and depressions 12 and 13 in the glass tube support the copper tube centrally disposed within the glass 75 tube 10.

To each end of the copper tube 11, I secure a spiral or rat-tail of copper wire as shown at 14 and 15, these spirals or rat-tails being firmly secured to, or formed integral 80 with suitable terminal hooks as shown at 16 and 17, the hooks being supported by cups 18 and 19 which serve as terminal cups for the glass tube. I may introduce a plastic metal as indicated at 20 and 21 within 85 the glass tube and surrounding the copper tube 11, the plastic metal assisting in retaining the tube in place and is so introduced, a small perforation 22 may be produced through the wall of the copper tube 11 90 for a purpose that shall appear later.

At 23 I show an exhausting tip such as is usually provided in incandescent lamps and for tubes or bulbs, the interiors of which are to be maintained under vacuum and when 95 my tube is constructed in the manner described, the passage through the tip 23 is open. This tip is connected to a suitable vacuum pump and the interior of the tube subjected to as near a complete vacuum as 100 possible and thereafter neon gas is admitted to the tube and the tip 23 closed by the application of heat thereto. The perforation 22 allows the interior of the copper tube 11 and the ends of the glass tube beyond the 105 restrictions 12 and 13 to be exhausted and

later allows the gas to pass into all parts of both the glass and copper tubes.

The presence of neon or any other suitable gas of high conductivity will add materially to the sensitiveness of the device as a whole and I consider the use of such gas important.

In Fig. 2, I show the substitution of a coil or spiral of wire as shown at 24. This wire is used in lieu of the copper tube 11. 10 The member 25 which may be of metal, is provided merely to support the spiral 24 and prevent the sagging thereof. If a spiral is employed, the glass tube may and should be of larger diameter as is the tube 26 and 15 in all constructions I may utilize the binding post 27 instead of the hooks 16 and 17.

I have found that a plurality of metallic tubes 28 and 29 may be arranged within the glass tube 30, as shown in Fig. 3.

20 The restrictions 12 and 13 in the glass tube 10 may be omitted and other means provided for supporting the inner metallic tube. In Figs. 4 and 7, I show a plurality of springs 31, 32, 33 and 34 separating the inner tube 35 and I have found that this inner tube may be of glass, coated with metal. Upon inserting the inner tube into the glass tube 36, the springs 31 to 34 are compressed and extending against the walls of the glass 25 tube 36, retain the inner tube in operative position. I may, however, provide a coil spring 37 which will assist in eliminating longitudinal movement of the inner tube.

In Figs. 5 and 6, the tube 38 is supported 35 by a metallic member formed with a hub 39 and a plurality of resilient arms is shown at 40. In Fig. 6, the resilient arms are shown as impinging upon the inner walls of the tube 41.

40 If it is necessary to utilize an antenna of greater length, a series of my devices may be connected in the manner shown in Fig. 8, where three tubes are shown in series, as at 11, 11' and 11'' or, as previously stated a 45 plurality of tubes may be arranged in the formation of a loop as shown in Fig. 9, where four tubes are so arranged as indicated at 11, 11^a, 11^b and 11^c. I have not found, however, that a plurality of tubes 50 are necessary or desirable, but the desirability or necessity of such an arrangement may be later discovered. I have employed my antenna tube within an ordinary receiving cabinet with very satisfactory results, 55 thus demonstrating its advantages for operable receiving sets.

In the construction shown in Figs. 10 and 11, the copper tube 45 is supported by means of insulating collars or rings 46 and 47 and 60 between these rings I arrange a tube 48

formed of wire mesh. The wire mesh is spaced away from the tube 45 and to this wire mesh 48 I secure a lead 49 from a source of electrical supply of comparatively high potential, the take-off from the copper mesh 65 consisting of a metallic plate 50 to which the other lead from the source of high potential current may be secured as shown at 51. The enclosing glass tube 52 is exhausted in the manner before described and 70 gas filled. The high potential current in the wire mesh 48 will set up an electronic discharge, which will serve as a means for agitating the gas within the tube, increasing its sensitiveness and conductivity of radio 75 active waves.

Other modifications may be made within the scope of the appended claims, without departing from the principle or sacrificing the advantages of the invention.

Having carefully and fully described my invention, what I claim and desire to obtain is:—

1. An antenna comprising a glass tube, a metallic tube therein and restrictions in said 80 glass tube to retain said metallic tube centrally disposed within said glass tube and means for preventing longitudinal movement of said metallic tube.

2. An antenna comprising a glass tube, a metallic tube therein and restrictions in said 90 glass tube to retain said metallic tube centrally disposed within said glass tube and means for preventing longitudinal movement of said metallic tube, said means comprising plastic metallic material surrounding said metal tube.

3. An antenna comprising a glass tube, a metallic tube therein, means in said glass tube to retain said metallic tube centrally 100 disposed within said glass tube and means for preventing longitudinal movement of said metallic tube, said means comprising plastic material surrounding said metal tube and flexible conductors secured to the ends 105 of said metallic tube and extending through said glass tube.

4. An antenna comprising a glass tube, a perforated metallic tube therein and restrictions in said glass tube to retain said metallic tube centrally disposed within said glass tube and means for preventing longitudinal movement of said metallic tube, said means comprising plastic material surrounding said metal tube and neon gas under pressure in said glass tube and beyond the restrictions therein.

Signed at the city, county and State of New York, this 4 day of June, 1923.

JOHN M. CLARK.
